UNITED STATES PATENT OFFICE.

ARTHUR A. VERRETTE, OF HAVERHILL, MASSACHUSETTS.

KNOCKDOWN FRUIT-BASKET.

1,050,407.

Specification of Letters Patent. Patented Jan. 14, 1913.

Application filed August 26, 1911. Serial No. 646,121.

To all whom it may concern:

Be it known that I, ARTHUR A. VERRETTE, a citizen of the United States, residing at Haverhill, in the county of Essex and State 5 of Massachusetts, have invented an Improvement in Knockdown Fruit-Baskets, of which the following is a specification.

This invention relates to certain improvements in knockdown baskets, especially that 10 class of open baskets which are used to contain small fruits.

The object of my invention is to provide a form of basket of the above described character, which may be readily cut out of 15 cardboard and bent into the desired form, or which may be provided in a flat blank, for shipment or storage, and formed into a basket when desired, without difficulty.

A further object is to provide a form of 20 corner clip for a basket of this character, which will act effectively to hold the parts in the desired position.

I accomplish these objects by the means shown in the accompanying drawing, in 25 which,

Figure 1 is a perspective view of a fruit basket made according to my invention. Fig. 2 is a plan view of the basket, blank, before it is folded. Fig. 3 is a detail view 30 of one of the corner clips, and Fig. 4 is a perspective view of a modified form of corner clip.

According to my invention I provide a blank adapted to be died from a sheet of 35 cardboard, or other material, which may be readily bent, said blank comprising a central bottom portion *a*, of approximately square form, four somewhat oblong-shaped side sections, or sides *b*, *c*, *d* and *e*, which 40 extend from the four side edges of the bottom outwardly therefrom, and a series of holding ears, or lugs, *b'*, *b''*, *c'*, *c''*, *d'*, *d''* and *e'*, *e''*, each pair of which extend from the opposite side of said sides. The line of connections of the several sections are scored to 45 permit them to be readily bent, as indicated in dotted lines. In forming the box the sides *b*, *c*, *d* and *e* are bent upwardly, and the ears are bent at right angles, so that the 50 ear of one side extends across the joint between said side and the adjacent side, and overlaps the latter.

A fastening clip is provided for each corner, which consists of a wire bent to form a 55 pair of spring clasps *f*, *f'*, connected by two intermediate portions *f²*, *f³*, and a bracing

portion *f⁴*, at the vertex of the angle between said portions *f²*, *f³*, formed by binding the wire in loop form at right angles thereto. The clasps *f*, *f'* are sufficiently 60 yielding to permit them to be forced astride the adjacent sides and overlapping ears, so as to press said sides and ears together, while the intermediate portion *b²*, *b²* rests against the inner surfaces of the sides and 65 presses the bracing portion *f⁴* into the corner, against the adjacent overlapping lug, thereby providing a strong reinforcement 70 for the corner, and assist materially in holding the box in shape. The action of the connecting portions *f²* and *f³* and the corner bracing portion *f⁴* of the clip are particularly 75 important in assisting to hold the basket in shape. In a flexible, angular shaped basket, like that described, there is 80 a strong tendency to press the sides outward when the basket is filled, that is, there is a tendency to force the walls into an approximately circular shape from the normal rectangular shape, causing the corners of the 85 basket to be drawn inwardly. With my particular form of clip such action is prevented, as said portions *f²*, *f³* and *f⁴* fit into and bear firmly against the corner portion 90 of the basket at its inner side, so that this 95 portion will not be drawn inwardly, but will be held square by the clip. These clips may be readily placed in position, as shown in Fig. 1, after the box has been folded into the form intended.

In Fig. 4 I show a slightly modified form *g* of corner clip, in which the portion corresponding to the middle bracing portion *f⁴* is omitted and the inner portion *g'*, *g''* merely intersect at an angle, and are pressed 95 into the corner of the basket. The function of this form of clip is substantially the same as that of the clip already described, but is less desirable, in that it does not brace the corner as efficiently as the other form.

I claim:

1. A knock-down basket comprising a blank having a bottom section, side sections extending therefrom and a laterally projecting ear at one side of each side section, each overlapping a corner of the basket and the inner side of the adjacent side section, and clips for connecting adjacent side sections at each corner, each comprising a pair of spring hooks arranged astride the adjacent 105 edge portions of the side sections and of the overlapping ears, the members of each

clasp within the basket having an angular connecting portion extending at approximately right angles thereto and formed to fit into the corner of the basket against the 5 inner side of the corresponding ear, said connecting portion having a vertically extending portion at its vertex arranged to bear against the ear at its bend transversely thereof to hold the basket corner from being drawn inwardly, substantially as described.

2. In combination with a basket having angularly arranged sides and overlapping staying portions at the corners, and stay 10 clips at each corner, each comprising a pair 15

of spring hooks arranged astride the adjacent edge portions of the sides, and an angular connecting portion arranged within the basket and formed to fit into the corner thereof against said staying portion, the 20 angle of said connecting portion corresponding to the angle between the sides, substantially as described.

In testimony whereof, I have signed my name to this specification, in the presence 25 of two subscribing witnesses.

ARTHUR A. VERRETTE.
